(57) **CLAIM**

The ornamental design for a panel for locks, as shown and described.

DESCRIPTION

FIG. 1 is a top, front and right side perspective view of a panel for locks showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a top, front and right side perspective view showing the panel for locks in a state of use.

The broken lines in the drawings illustrate portions of the panel for locks which form no part of the claimed design.
